(57) **CLAIM**

I claim the ornamental design for device to secure container to reciprocating power tool, as shown and described.

DESCRIPTION

This application claims priority to U.S. Patent Application Ser. No. 11/934,749 which is titled Device To Secure Container To Reciprocating Power Tool filed on Dec. 19, 2007 to Blair.

FIG. 1 is an overhead oblique view of a device to secure container to reciprocating power tool.

FIG. 2 is also an overhead oblique view of the device to secure container to reciprocating power tool shown in FIG. 1; and,

FIG. 3 is another overhead oblique view of the device to secure container to reciprocating power tool shown in FIG. 1.

The broken lines showing the container in FIG. 3 are for illustrative purposes only and form no part of the claimed design.
